UNITED STATES PATENT OFFICE.

ALBERT CHRISTIAN OEHRLE, OF PHILADELPHIA, PENNSYLVANIA, ASSIGNOR
TO OEHRLE BROS. & CO.

DESIGN FOR FRINGE.

SPECIFICATION forming part of Design No. 29,348, dated September 13, 1898.

Application filed August 11, 1898. Serial No. 688,401. Term of patent 14 years.

To all whom it may concern:

Be it known that I, ALBERT CHRISTIAN OEHRLE, a citizen of the United States, residing in the city and county of Philadelphia and State of Pennsylvania, have invented and produced a new and original Design for Fringe, of which the following is a specification, reference being had to the accompanying drawings, forming a part thereof.

10 In the accompanying drawings I have illustrated an embodiment of my new design, in which—

Figure 1 is a representation of the obverse side of a section of the fringe, and Fig. 2 is a 15 similar representation of the reverse side of the fringe.

The essential feature of my new design comprises a gimp or heading, along the lower portion of which, on the obverse side, the fringe-threads are arranged in the form of loops, the threads between the loops forming substantially inverted-V-shaped portions, and from the loops, adjacent to the lower edge of the heading, portions of the fringe-threads 20 passing through the loops are united to form knots, below which extend the tufts, and on the reverse side the threads of the fringe are in parallel groups along the lower edge of the

heading, and portions of the groups of threads passing through two adjacent loops are united 30 to form knots below and intermediate vertical planes passing through the loops, and these combined portions terminate in tufts.

Thus, in the drawings, A represents the gimp or heading of the fringe, and B the tufts, 35 while the fringe-threads C, starting from the point c', are arranged in the form of loops c², the threads of the loops crossing each other and forming substantially inverted-V-shaped upper portions c² between the loops, while below the loops portions of the threads passing through two adjacent loops are brought together, forming knots c⁴ below the loops and intermediate between two adjacent loops, and below the knots extend the tufts B. 40 45

What I claim is—

The design for fringe, substantially as shown and described.

In testimony whereof I have signed my name to this specification in the presence of 50 two subscribing witnesses.

ALBERT CHRISTIAN OEHRLE.
